United States Patent Office

Des. 212,789
Patented Nov. 19, 1968

212,789

PENCIL SHARPENER

Richard M. Kipp, 161 Hunter's Lane,
Devon, Pa. 19333

Filed Aug. 4, 1967, Ser. No. 8,124

Term of patent 3½ years

(Cl. D74—21)

FIG. 1

FIG. 2

FIG. 3

FIG. 4

FIGURE 1 is a side elevational view of a pencil sharpener showing my new design.

FIGURE 2 is a front elevational view of the pencil sharpener shown in FIGURE 1, the back thereof being a mirror image of the front.

FIGURE 3 is a side perspective view thereof.

FIGURE 4 is another side perspective view thereof as it appears adapted for a wall mounting.

I claim:

The ornamental design for a pencil sharpener, as shown and described.
